DESIGN FOR A COMBINED LAMP, SMOKING STAND, AND RADIO TUNING UNIT

Daniel J. Crowley, Grosse Pointe, Mich.

Application November 15, 1937, Serial No. 72,894

Term of patent 14 years

To all whom it may concern:

Be it known that I, Daniel J. Crowley, a citizen of the United States of America, residing at Grosse Pointe, in the county of Wayne and State of Michigan, have invented a certain new, original, and ornamental Design for a Combined Lamp, Smoking Stand, and Radio Tuning Unit, of which the following is a specification, reference being had therein to the accompanying drawing, forming a part thereof, wherein; the single figure is a perspective view of a combined lamp, smok-

ing stand and radio tuning unit embodying my new design.

The characteristic features of my design reside in the portions illustrated in solid black lines in the drawing.

I claim:

The ornamental design for a combined lamp, smoking stand and radio tuning unit substantially as shown and described.

DANIEL J. CROWLEY.
